UNITED STATES PATENT OFFICE.

MARCUS C. STEESE, OF DULUTH, MINNESOTA.

MEANS FOR PREVENTING THE ESCAPE OF INCLOSED GAS.

Application filed February 16, 1920. Serial No. 358,986.

To all whom it may concern:

Be it known that I, MARCUS C. STEESE, a citizen of the United States, residing at Duluth, in the county of St. Louis and State of Minnesota, have invented certain new and useful Improvements in Means for Preventing the Escape of Inclosed Gas, of which the following is a specification.

This invention relates to means for preventing the escape of gases inclosed within receptacles, such, for example, as gas producers.

One object of the invention is to provide simple, novel and efficient means for effectively sealing receptacles which contain gas, in a manner such that the escape of such gas through an opening through which a member is movable is obviated.

Another object is to provide simple, compact and reliable means for packing poker shanks at the point where the latter pass through the wall of a gas producer.

Another object is to provide simple and efficient packing around a rod which does not depend upon a metal-to-metal contact.

These and other objects are accomplished by means of the arrangement disclosed on the accompanying sheet of drawings, in which—

30 Figure 1 is a fragmentary sectional view of a gas producer embodying my invention;

Figure 2 is a sectional view through an attachment for a gas producer embodying my improved sealing means;

35 Figure 3 is a top plan view of the same;

Figure 4 is a top plan view of one of the segmentally-formed rings forming a part of my gas sealing means; and,

40 Figure 5 is a transverse sectional view of the same ring arrangement.

The various novel features of my invention will be apparent from the following description and drawings and will be particularly pointed out in the appended claims.

45 In metallurgical operations it is necessary to equip apparatus for handling gas containing tarry vapors with some kind of water-seals or packing which will prevent the leak of gas around valve stems and poker. The movable parts around which the packing must fit, namely, the valve stems or poker, are subjected to a reciprocating motion, sometimes vertical, and at the same time frequently are required to move in a decided lateral direction. Owing to the fact that the gas to be handled

carries large amounts of vapors of tar and like oils, it is not practicable to pack them as it is customary to pack the piston rod of engines which do not have a wide lateral motion and where there are no tar vapors to contend with. It is almost universal practice to seal the leak of gas around the rod or poker of a gas producer by means of a water-seal. This water-seal, as is well known, consists of an inverted cup dipping into a chamber containing water. Obviously, the length of the inverted cup must be equivalent to the maximum vertical movement of the poker plus sufficient depth of water to withstand the pressure inside the vessel. Furthermore, a constant flow of water is necessary to compensate for the constant evaporation or overflow that takes place from the water-seal.

50 My invention comprises a new and useful means for forming a packing around a rod or poker and depends for its efficiency upon the presence of tar vapors and oils which are utilized in my mechanism for the prevention of the escape of gas. In fact, in starting up the mechanism before it has received, by condensation of vapors, a sufficient quantity of tar and oils to make it effective, I preferably pour into the mechanism enough of such material to form a perfect seal. In this respect the packing differs fundamentally from steam packing, which depends for its efficiency upon a metal-to-metal contact. In my construction 55 I distinctly and purposely avoid metal-to-metal contact to prevent the escape of gas, and depend upon the sealing action which is obtained from the tar and oils contained in the gas.

55 Referring to the figures of the drawings, it will be noted that I have shown a gas producer 10, the upper part of which has a plate 11 to which my sealing arrangement is attached. Among other things, the attachment includes a casting 12 having a chamber 13, which is covered by a plate 14, the latter being secured to the casting 12 by any suitable means, such as bolts 15. The plate 14 is provided with an enlarged opening 16 and the floor 17 of the chamber 13 likewise is provided with an enlarged opening 18 through which the rod or shank 19 of the poker moves. As is well known in the art, the function of the poker of a gas producer is to penetrate the carbonaceous material in the body of the producer and

primarily in the coking zone thereof, for maintaining the body of the coke in a uniformly porous condition. To do this it is well understood that the poker, and therefore its rod 19, is moved up and down vertically and also laterally because of the relative rotation between the body of the gas producer and the top thereof. Accordingly, the openings 16 and 18 in the plate 14 and floor 17 are enlarged to permit the necessary lateral movement of the poker rod 19. Mounted within the chamber 13 and loosely fitting around the poker rod 19, are upper and lower solid follower plates 20 and 21, respectively. Interposed between these follower plates and loosely surrounding the poker rod 19 are a plurality of packing rings 22, each of which preferably is formed of a plurality of segments 23 held in cooperative position by a coiled spiral spring 24. Each of the rings 22 has formed adjacent the poker rod 19 an annular groove 25 for the reception and collection of condensed tar or oil vapors to form, in part, a seal at the opening through which the poker rod 19 passes. These packing rings 22 and the follower plates 20 and 21 have rough unfinished surfaces so that although they make contact metal to metal at certain points, they are purposely left in an unfinished state in order to provide at all times a film or coating of tar or oil, or both, between their operating surfaces, which assists in providing a perfect seal. Necessarily, the combined thickness of the packing rings 22 and the follower plates 20 and 21 is less than the vertical dimension of the chamber 13, and the overall diameter of said rings and plates is less than the internal diameter of said chamber, so that said packing rings and plates with the poker rod are free to move laterally in said chamber. It will be noted that the poker rod 19 is loosely mounted within the rings 22 and plates 20 and 21, the space therebetween being filled by condensed tar or oil vapors, said relatively viscous fluids completely filling the space between the rings and follower plates, between the follower plates and the cover plate 14 and the floor 17 of the chamber, and between such parts and the poker rod 19, forming a perfect seal against the escape of gas through the opening through which the poker passes. These tar and oil vapors are produced during the production of gas and the distillation of the coal in the gas producer, and collect in my packing mechanism in a condensed viscous form to maintain the seal in question. It will be understood, of course, that the temperature to which this sealing mechanism is exposed is sufficiently low to produce condensation of the tar and oil vapors contained in the gas. Consequently, all of the parts thereof remain constantly coated with tar and oil.

In starting up the apparatus before any tar or oil vapors have been formed, the chamber 13 may be provided with any suitable relatively viscous material, such as heavy oil for forming the seal, the sealing material being supplied through a normally closed plug opening 26 in the cover plate 14. In practice I have found it is rarely necessary to refill the chamber 13, inasmuch as the condensation compensates for the leakage which would otherwise take place. In case pitch forms in the mechanism, the same can be readily loosened by the use of kerosene applied through the plug opening 26. In this connection it may be stated that there is more or less of a tendency for pitch or tar to bake or harden on the poker rod 19 in the neighborhood of the follower plate 21. The poker rod 19, however, is maintained clean by such follower plate, in view of the fact that the latter is solid and serves to shear off any accumulated material within practical limits. This plate, however, does not fit so closely as to prevent tar vapors from accumulating in the grooves 25 and between the plates in question.

It is my intention to cover all modifications of the invention falling within the spirit and scope of the following claims.

I claim:

1. A gas producer wall provided with a poker rod opening, and means to prevent the escape of gases around the poker rod, said means comprising a plurality of sealing members having openings adapted to register in alignment with the poker rod opening and of substantially the same diameter as that of the poker rod, the walls of the respective openings being provided with seats for the reception of viscous material formed by the condensation of vapors emitted from the gas. 100
2. A gas producer wall provided with a poker rod opening, and means to prevent the escape of gases around the poker rod, said means including a plurality of discs having openings adapted to register and receive the poker rod, the walls of the openings having annular grooves to receive viscous material formed by the condensation of the vapors emitted by the gas, each disc being formed in segments and provided with a contractile spring embracing the segments and holding them in assembled relation. 110
3. A sealing device for the poker rods of gas producers comprising a chamber having inner and outer aligned poker rod openings, and a plurality of sealing members contained within the chamber and provided with openings adapted to register in alignment with the openings in the chamber, the walls of the openings of said sealing members being provided with annular grooves for the reception of viscous material produced by the condensation of vapors emitted 120

from the gases of the gas producer to produce a seal between the poker rod and the walls of the openings.

4. A sealing device for the poker rods of gas producers comprising a chamber having inner and outer aligned poker rod openings, and a plurality of sealing members contained within the chamber and provided with openings adapted to register in alignment with the openings in the chamber, the walls of the openings of said sealing members being provided with annular grooves for the reception of viscous material produced by the condensation of vapors emitted from the gases of the gas producer to produce a seal between the poker rod and the walls of the openings, the chamber being provided with an opening and a removable closure for said opening.
5. A sealing device for the poker rods of gas producers comprising a chamber having inner and outer aligned poker rod openings, and a plurality of sealing members contained within the chamber and provided with openings adapted to register in alignment with the openings in the chamber, the walls of the openings of said sealing members being provided with annular grooves for the reception of viscous material produced by the condensation of vapors emitted from the gases of the gas producer to produce a seal between the poker rod and the walls of the openings, the diameters of the sealing members being less than the internal diameter of the chamber to permit edgewise movement of the sealing members, and the openings in the inner and outer walls of the chamber being larger than the openings in the sealing members to permit angular movements of a poker rod.
6. A sealing device for the poker rods of gas producers comprising a chamber having inner and outer aligned poker rod openings, and a plurality of sealing members contained within the chamber and provided with openings adapted to register in alignment with the openings in the chamber, the

walls of the openings of said sealing members being provided with annular grooves for the reception of viscous material produced by the condensation of vapors emitted from the gases of the gas producer to produce a seal between the poker rod and the walls of the openings, the chamber being provided with an opening and a removable closure for said opening.

7. A sealing device for the poker rods of gas producers, comprising a chamber having a removable outer end and an inner attaching flange, the inner and outer ends of the chamber being provided with aligned openings to receive a poker rod, said openings being bevelled to permit angular movements of the poker rod, and a plurality of sealing discs within and of less diameter than the chamber and capable of edgewise movement therein to accommodate angular movements of a poker rod, each sealing disc having an opening for the reception of a poker rod and the wall of the opening being provided with an annular groove, each disc also being formed of segments, and springs embracing the respective discs for holding the segments assembled.

Signed at Duluth, Minnesota, this 9th day of February, 1920.

MARCUS C. STEESE.
